United States Patent Office

Des. 232,431
Patented Aug. 20, 1974

232,431

WHEEL

David V. Kimball, 1817 W. Anamaker, Covina, Calif.
91723, and Daniel L. Baughn, 16059 Double Grove,
Valinda, Calif. 91744

Continuation-in-part of design applications Ser. No.

204,793 and Ser. No. 204,794, both Dec. 3, 1971.

This application Aug. 7, 1972, Ser. No. 278,298

Term of patent 14 years

Int. Cl. D12—16

U.S. Cl. D12—205

FIG. 1.

1

3

FIG. 2.

FIG. 3.

FIG. 4.

FIG. 5.

FIG. 6.

FIG. 1 is a front elevational view of a wheel showing our new design;

FIG. 2 is a side elevational view thereof;

FIG. 3 is a sectional view thereof taken along the line 3-3 in FIG. 1;

FIG. 4 is a front elevational view of a wheel showing a second embodiment of our new design;

FIG. 5 is a side elevational view of the wheel shown in FIG. 4; and

FIG. 6 is a sectional view of the wheel shown in FIG. 4 taken along the line 6-6 in FIG. 4.

This is a continuation-in-part of design application Ser. No. 204,793 and 204,794, both having been filed on Dec. 3, 1971 and now abandoned.

We claim:

The ornamental design for a wheel, as shown and described.
